EDUCATIONAL COLOR WHEEL

Ellis H. Robinson, Bldg. 328, Paine Field,
Everett, Wash. 98204

Filed Nov. 26, 1973, Ser. No. 418,888

Term of patent 14 years

Int. Cl. D19—07

U.S. Cl. D19—59

FIG. 1

FIG.2

FIG.3

FIG. 1 is a view of the face of the educational color wheel, showing my new design;

FIG. 2 is a side elevational view of the educational color wheel; and

FIG. 3 is a view of the back face of the educational color wheel.

I claim:

The ornamental design for an educational color wheel, substantially as shown.
